UNITED STATES PATENT OFFICE.

BYRON J. BALLIETT, OF MANSFIELD, OHIO.

SUSPENDER-LINK.

No. 843,987.

Specification of Letters Patent.

Patented Feb. 12, 1907.

Application filed February 23, 1905. Serial No. 247,049.

To all whom it may concern:

Be it known that I, BYRON J. BALLIETT, a citizen of the United States of America, and a resident of Mansfield, Richland county, Ohio, 5 have invented certain new and useful Improvements in Suspender-Links, of which the following is a specification.

My invention relates to an attachment for suspenders, and is especially designed to improve the device shown and described in a patent granted to me bearing the date of February 4, 1902, No. 692,595.

The objects of my invention are to construct an attachment for suspenders of two 15 separate parts having cross-bars or journals, upon which crown-rollers are mounted, and means to pivotally connect said parts to admit of independent movement.

Similar letters of reference refer to similar 20 parts throughout the several views.

I attain these and other objects by the mechanism illustrated in the accompanying drawings, in which—

Figure 1 is a plan view of my device showing the parts comprising the attachment in closed position with the straps of the suspender in dotted lines. Fig. 2 is a plan view showing the lower part upon which a lower roller is journaled swung out of proper position and dotted lines showing position when in use. Fig. 3 shows a blank of the desired shape to form the rollers. Figs. 4 and 5 are detail views of the crown-rollers. Fig. 6 is a cross-sectional view of the attachment or link, 35 taken on the line X X of Fig. 2, showing inner link-forming part of the attachment swung out of position and dotted lines showing position of inner link when in use.

In the construction of my attachment for 40 suspenders I prefer to use round wire to pre-

vent undue friction on the edges of the straps when irregular movement is imparted to the body of the wearer. The outer and upper part *a* of the attachment is formed to the required shape, leaving the upper portion 45 straight to form a journal *a'* for the crown-roller *B*. These free ends *c* and *d* of both parts are turned inwardly in alinement with each other. The lower part *e* swings within the upper part, bringing the roller *B*, mounted on the upper portion *a'*, parallel with and directly underneath the upper roller, which is mounted on the upper portion *a'*. The free ends of both parts are pivotally connected by the hollow sleeve *f* to permit each 55 part to move freely and independently of each other when subjected to unequal strain.

Having fully described my invention, what I claim, and desire to secure by Letters Patent, is—

In an attachment for suspenders comprising a two-part link, one of said link parts adapted to swing within the other, both of said link parts having their ends turned inwardly parallel with each other, a hollow 65 band to pivotally connect said link parts together to permit independent movement; said link parts having their upper portions formed straight to provide journals, both straight portions lying parallel with each 70 other when in use, antifriction crown-rollers rotatably mounted upon said straight portions of said link parts.

Signed at Mansfield, Ohio, this 20th day of February, 1905.

BYRON J. BALLIETT.
